CIRCUIT INTERRUPTER

Albert P. Strom, Forest Hills, Pa., assignor to
Westinghouse Electric Corporation, East Pitts-
burgh, Pa., a corporation of Pennsylvania

Application October 4, 1944, Serial No. 557,078

21 Claims. (Cl. 200—150)

1

This invention relates to circuit interrupters, in general, and, more particularly, to arc extinguishing structures therefor.

A general object of my invention is to provide a circuit interrupter of improved construction which will more effectively interrupt the circuit therethrough than has been achieved heretofore.

My invention relates to circuit interrupters in which properly controlled flow in the region of the arc is used to bring about interruption. Where the flow is produced by a separate energy source, rather than by the arc itself, the flow is generally more effective, since such flow is independent of the current magnitude, and the interrupter can be made to operate successfully over a larger current range. Self-energized flow usually results in insufficient flow at low currents, and excessive flow and pressures at high currents. On the other hand, self-energized flow eliminates the need of additional sources of energy. It is an object of my invention to obtain most of the advantages of a device having separately energized flow without the use of a separate energy source.

A more specific object of my invention is to provide an improved circuit interrupter in which pressure from a pressure-generating arc is stored until it attains a sufficient pressure to readily effect the interruption of a serially related interrupting arc, at which time the pressure adjacent the pressure-generating arc is suddenly released to quickly effect the extinction of the interrupting arc to thereby interrupt the electrical circuit passing through the interrupter.

Another object of my invention is to provide an improved circuit interrupter in which a pressure-generating arc is established within a pressure-generating chamber and an interrupting arc is established within an interrupting chamber with improved means permitting inter-communication between the two chambers upon the attainment of a predetermined rise of pressure within the pressure-generating chamber.

Another object is to provide an improved circuit interrupter in which the pressure adjacent the pressure-generating arc is utilized for creating a superimposed pressure adjacent the point of initial establishment of the interrupting arc. Also preferably I employ a higher pressure created adjacent the pressure-generating arc to cause a flow of fluid under high pressure from the pressure-generating arc toward the interrupting arc, the latter being established in the region of superimposed pressure.

In general, the scheme consists of a pressure-generating arc in series with the interrupting arc,

2

but the pressure-generating arc is located in a chamber separated from that in which the main interrupting arc is drawn. The pressure-generating arc is drawn first, before the interrupting contacts part. It builds up a predetermined pressure in the pressure-generating chamber, which preferably has one wall in the form of a piston held in position by a strong spring, so that as gas is formed the volume of the chamber may expand.

10 Then when pressure reaches a predetermined value a port is opened between it, and the interrupting chamber. The interrupting contact now opens, and the arc is extinguished by the flow of oil or gas from the pressure-generating chamber. 15 This flow is thus essentially independent of current magnitude. On low currents a little longer time is required to store the energy, but the velocity of flow when the contacts open is practically the same for both large and small currents. The 20 flow of gas or liquid toward the interrupting arc is essentially independent of the amperage of the interrupting arc since it is produced by the stored energy within the pressure-generating chamber.

Further objects and advantages will readily be 25 come apparent upon a reading of the following specification taken in conjunction with the drawings, in which:

Figure 1 is a vertical sectional view through a 30 circuit interrupter embodying my invention and shown in the closed circuit position;

Fig. 2 is a sectional view taken along the line II—II of Fig. 1;

Fig. 3 is a fragmentary view of a portion of the 35 contact structure utilized for establishing the pressure-generating arc;

Fig. 4 is a sectional view taken along the line IV—IV of Fig. 3;

Fig. 5 is an elevational view partially in section 40 of a circuit interrupter embodying a modification of my invention and being shown in the closed circuit position;

Fig. 6 is a vertical sectional view through the 45 left-hand arc extinguishing unit of Fig. 5, the parts being shown in the partly open circuit position;

Fig. 7 is a vertical sectional view through a 50 modified type of circuit interrupter embodying my invention, the parts being shown in the closed circuit position; and

Fig. 8 is a sectional view taken along the line 55 VIII—VIII of Fig. 7 taken on a reduced dimensional scale.

Referring to the drawings and, more particularly, to Figs. 1—4 thereof, the reference numeral 60 1 designates a metallic casing filled to the level 2

with a suitable arc extinguishing fluid 3 in this instance circuit breaker oil. A metallic plate 4 encloses the lower end of the casing 1, being secured thereto by any suitable means such as welding 5. The upper end of the casing 1 is apertured as at 6 and through this aperture an insulating casing 7 extends having a shoulder portion 8 which seats upon the periphery of the aperture 6, a resilient gasket 9 preferably being provided.

The upper end of the insulating casing 7 is closed by a metallic cap 10 which is secured threadedly at 11 to the upper end of the casing 7. A metallic cylinder 12 is threadedly secured at 13 to the lower end of the casing 7, the lower end of the cylinder 12 being attached to the plate 4 by any suitable means (not shown). Exhaust apertures 4 are provided adjacent the lower end of the cylinder 12.

Reciprocally movable within the cylinder 12 is a piston member 15, in this instance comprising a disc of insulating material. Threadedly secured at 16 to the piston member 15 is an insulating piston sleeve 17 which slides adjacent the inner wall of the cylinder 12. Rigidly secured to the piston member 15, and preferably threaded thereto at 18 is an insulating piston rod 19, having the upper portion thereof provided with a bore 20 in which slidably moves an enlarged spider portion 21 secured to the bottom of a movable interrupting contact 22. A contact actuating member 23 having apertures 24 provided therethrough is threadedly secured at 25 to the upper portion of the bore 20. Also the upper portion of the piston rod 19 has a plurality of grooves or flutes 26 formed therein, the purpose for which will appear more clearly hereinafter. The piston rod 19 slides with a relatively close fit through an aperture 27 formed in a partition member 28 formed of insulating material and threadedly secured at 29 to the upper end of the cylinder 12.

From the above description it will be apparent that the partition member 28 cooperates with the cylinder 12, piston sleeve 17 and piston member 15 in forming a substantially enclosed pressure-generating chamber generally designated by the reference numeral 30.

Within the substantially enclosed pressure-generating chamber 30 is disposed a contact structure generally designated by the reference numeral 31 and in this instance comprising two contacts 32 secured to the piston member 15 and movable therewith, being joined at their lower ends by a conducting bar 33. The contact structure 31 also comprises a pair of contacts 34 threadedly secured to a conducting ring-shaped member 35 disposed within the pressure-generating chamber 30 and surrounding the piston rod 19. The contact structure 31 is cooperable to establish a pressure-generating arc within the pressure-generating chamber 30. By employing two pairs of contacts 32, 34 there results symmetry and longer contact life, since the pressure-generating arc will sometimes be drawn on one pair of contacts 32, 34 and sometimes on the other pair of contacts 32, 34. Also threadedly secured to the conducting ring-shaped member 35, as more clearly shown in Fig. 3, are a pair of conducting bolts 36 having insulating sleeves 37 disposed therearound which slide with a relatively close fit through apertures 38 provided in the piston member 15. At the lower end of the conducting bolts 36 are secured flexible shunts 39, the other ends of which are electrically connected to bolts 40, only one of which is shown in Fig. 1 and acts as a line terminal.

Referring to Fig. 3 it will be observed that

compression springs 41 encircle the insulating sleeves 37 between the ring-shaped member 35 and the piston member 15, thereby biasing the contacts 34 upwardly away from the contacts 32. However, in the closed circuit position as shown in Fig. 1, a plurality, in this instance four insulating operating rods 42 extending upwardly through the partition member 28 through an insulating plate 43, joined at their upper ends by a plate 44, and biased downwardly by a compression spring 45, serve to hold the contacts 32, 34 in abutting engagement.

An armature member 46 is secured to the plate 44 and slidably moves within the bore 47 of a solenoid 48, which is preferably disposed in series circuit so that the armature 46 is responsive to overload conditions existing in the series electrical circuit controlled by the interrupter.

Consequently, in the closed circuit position of the interrupter as shown in Fig. 1, the electrical circuit therethrough comprises the terminal stud 49, connector 50, solenoid 48, connector 51, stationary interrupting contact 52, movable interrupting contact 22, conducting spider portion 21, flexible conductor 53, conducting rod 54, conducting bar 33, contacts 32, contacts 34, conducting ring-shaped member 35, conducting bolts 36, flexible shunts 39 to the terminal bolt 40.

The stationary and movable interrupting contacts 52, 22 collectively form a first contact structure cooperable to establish an interrupting arc, not shown, within a substantially enclosed interrupting chamber generally designated by the reference numeral 56. The upper end of the interrupting chamber 56 is substantially closed by a suitably shaped insulating member 57 forming an orifice 58 and being provided with a plurality of fluid conducting passages 59 which lead from the region 56 to the orifice 58.

The movable interrupting contact 22 has a flange 60 integrally formed therewith which moves downwardly during the opening operation into an annular recess 61 formed by the insulating member 57.

From the foregoing description it will be apparent that the contact actuating member 23, spider portion 21 and compression spring 62 collectively form a lost-motion mechanical connection generally designated by the reference numeral 63 interconnecting the piston member 15 and the movable interrupting contact 22 of the first contact structure 55.

A compression spring 64 seated on the plate 4 biases the piston member 15 upwardly toward its closed circuit position. Stops 65 secured as by welding to the plate 4 may be provided to stop the downward movement of the piston member 15.

The operation of the interrupter will now be explained. During the existence of overload conditions in the circuit controlled by the interrupter the solenoid 48 will draw the armature 46 upwardly against the downward biasing force of the compression spring 45, thereby moving the plate 44 and the operating rods 42 upwardly thus permitting the compression springs 41 to move the ring-shaped member 35 upwardly away from the piston member 15 separating the second contact structure 31 to establish a pressure-generating arc within the pressure-generating chamber 30. The pressure-generating arc will react upon the oil completely filling the pressure-generating chamber 30 to form gas which will cause the pressure-generating chamber 30 to be expanded by causing the downward movement of the piston member 15 against the upward biasing action

of the compression spring 64. During the downward movement of the piston member 15, the movable interrupting contact 22 will remain in engagement with the stationary interrupting contact 52 because of the upward biasing action of the compression spring 62 disposed in the bore 20 of the piston rod 19.

Pressure within the pressure-generating chamber 30 will rise to cause continued downward movement of the piston member 15 and piston rod 19, until the piston member 15 approaches the stops 65. When this occurs the contact actuating member 23 will engage the spider portion 21 in abutting engagement to forcibly cause the movable interrupting contact 22 to move downwardly away from the stationary interrupting contact 52, thereby causing a separation of the first contact structure 55 to draw an interrupting arc within the orifice 58 disposed at the upper end of the substantially enclosed interrupting chamber 56.

Also at this time the grooves or flutes 26 pass below the wall means or partition member 28 to thereby cause an intercommunication between the pressure-generating chamber 30 and the interrupting chamber 56 to permit the gas and oil under pressure to flow upwardly out of the pressure-generating chamber 30 through the flutes 26 past the wall means 28 upwardly into the interrupting chamber 56 and out of the interrupting chamber 56 adjacent the interrupting arc through the orifice 58 to thereby cause an extinction of the interrupting arc.

The extinction of the interrupting arc breaks the electrical circuit through the interrupter, thus also causing the extinction of the pressure-generating arc. Because of the compression springs 64, 62, and 45 the movable parts of the interrupter will gradually move toward their closed circuit positions as shown in Fig. 1, the speed of motion depending upon the leakage of oil past the moving parts of the interrupter. Suitable disconnect means disposed in series circuit may be employed or the movable parts of the interrupter may be latched to their full open circuit position.

From the foregoing description it will be apparent that I have provided an improved interrupter which stores the pressure created adjacent the pressure-generating arc until it assumes a value sufficient to effectively cause the interruption of the interrupting arc, at which time opening means are actuated through the wall means 28 separating the interrupting chamber from the pressure-generating chamber to thereby permit gas and oil under pressure to flow through the opening means 26 past the wall means 28 into the interrupting chamber 56 to cause an extinction of the interrupting arc.

It will be noted that the volume of the pressure chamber 30 increases a predetermined amount before drawing the interrupting arc. It is important that the volume of gas generated also be sufficient; otherwise not enough flow for interruption will occur. Both the pressure and volume are controlled in the present invention.

The rate of reclosure of the movable parts of the interrupter may be regulated by providing the proper size of vent holes 28a between chamber 30 and the other parts of the breaker. The breaker may be provided with suitable lockout mechanism to hold it open after a single or a pre-determined number of operations.

An overpressure safety device is included in that the pressure within the pressure-generating

chamber 30 tends to reclose the second contact structure 31 against the bias of the two compression springs 41 by expelling the bolts 36 and sleeves 37 out of the pressure chamber 30. Thus, if too sudden a pressure is generated in the pressure-generating chamber 30, contacts 34 will reclose against contact 32 so that the pressure-generating source temporarily disappears. Then as soon as piston 15 moves downwardly and thereby relieves the pressure, contacts 34 will again raise to again open the second contact structure to supply the pressure as needed because of the opening bias of compression springs 41. It is evident, that contacts 34 can be made to reclose at any desired overpressure since they will close when the chamber pressure within pressure-generating chamber 30 times the cross-sectional area of sleeves 37 and bolts 36 exceeds the force of springs 41.

From the foregoing it is apparent that I have provided novel means for shortening the length of the pressure-generating arc upon the attainment of excessive pressure within the pressure-generating chamber 30.

In the embodiment of my invention shown in Figs. 5 and 6 an arrangement is shown whereby the novel interrupting structure which I disclose may be used in a conventional tank in which may be operated the conventional movable conducting bridging member actuated by the vertical insulating operating rod. More specifically, referring to Fig. 5 the reference numeral 68 designates a tank filled to the level 69 with a suitable arc extinguishing fluid 70 in this instance circuit breaker oil. Depending from the cover 71 of the tank 68 are two insulating bushings 72 through which terminal studs 74, 75 extend.

Threadedly secured to the lower ends of the terminal studs 74, 75 are contact feet 76, 77 which rigidly support in position two identical arc extinguishing units generally designated by the reference numeral 78. A conducting bridging member 79 actuated reciprocally in a vertical direction by an insulating operating rod 80 electrically interconnects in the closed circuit position, as shown in Fig. 5, the two arc extinguishing units 78.

Referring more particularly to Fig. 6 which shows in vertical section the left-hand arc extinguishing unit 78 of Fig. 5, it will be observed that the arc extinguishing structure is the same as was previously described in connection with Figs. 1-4. However, the contact foot 76 is threadedly secured at 81 to the upper end of the metallic cylinder 12.

The lower end of the insulating casing 7 is closed by a conducting plate 82 rigidly secured in place by bolts 83. The stationary interrupting contact 52 is threadedly secured at 84 to the conducting plate 82. Stationary disconnect contacts 85 are provided externally of the plate 82 being rigidly secured thereto by bolts 86. A movable disconnect contact 87 biased upwardly by a compression spring 88 makes engagement in the closed circuit position as shown in Fig. 5 with the stationary disconnect contacts 85. The lower end of the movable disconnect contact 87 is electrically connected by a conductor 89 to the conducting bridging member 79 by a bolt 90.

The compression spring 88 is disposed within a metallic housing cylinder 91 forced by a pressed fit into an aperture 92 provided at the extremity of the bridging member 79. A compression spring 93 encircles the housing 91 and biases upwardly a cup-shaped member 94, the upper end

of which engages in abutting relation a ring-shaped metallic plate 95 to which the insulating operating rods 42 are threadedly secured at 96.

The upward movement of the cup-shaped member 94 is determined by a flange portion 97 integrally formed with the housing 91.

Consequently, in this embodiment of my invention it is apparent that in place of the electromagnetic device 48 which was used in Fig. 1, a mechanically actuated device, generally designated by the reference numeral 98 is employed to effect initial downward movement of the operating rods 42 as determined by downward movement of the insulating operating rod 80. A compression spring 99 biases the operating rods 42 secured to the ring-shaped plate 95 downwardly.

Consequently, from the foregoing description it is apparent that to open the electrical circuit passing through the interrupter shown in Figs. 5 and 6, the operating rod 80 is moved downwardly by suitable means, not shown. This causes downward movement of the conducting bridging member 79 which permits the compression spring 99 to force the operating rods 42 downwardly. This establishes a pressure-generating arc 100 within the pressure-generating chamber 30 as shown in Fig. 6. Following a predetermined upward travel of the insulating piston member 15 the contact actuating member 23 engages the spider portion 21 to cause upward movement of the movable interrupting contact 22 to thereby cause an interrupting arc 101 to be drawn within the orifice 58. The flutes 26 passing through the wall means 28 permit oil and gas under pressure to pass from the pressure-generating chamber 30 through the flutes 26 into the interrupting chamber 56 adjacent the arc 101 within the orifice 58 and out the exhaust ports 102 disposed in the insulating casing 7. During this time the movable disconnect contact 87 remains in engagement with the stationary disconnect contact 85 so that the interrupting of the circuit takes place within the arc extinguishing unit 78 and not exteriorly thereof at the contacts 85, 87. However, following interruption of the circuit the movable disconnect contact 87 separates from the stationary disconnect contact 85 to introduce an isolating gap into the circuit as shown more clearly by the dotted lines 103 in Fig. 5.

From the foregoing description it is apparent that my invention is readily adapted to a circuit breaker construction in which two arc extinguishing units are disposed within a tank structure and are electrically interconnected by a conducting bridging member vertically actuated by an insulating operating rod 80.

In the embodiment of my invention shown in Figs. 7 and 8, I provide means for utilizing pressure generated at the pressure-generating arc to establish superimposed pressure adjacent the interrupting contact structure prior to the opening of the interrupting contact structure. Subsequently, I employ a higher pressure generated at the pressure-generating arc for effecting fluid flow toward the interrupting arc when the latter is established in a medium of superimposed pressure.

More specifically, referring particularly to Fig. 7, the reference numeral 106 designates a tank structure having a partition member 107 provided intermediate its ends. Fluid 108, in this instance circuit breaker oil, fills the tank 106 to the level 109, one or more vent holes 110 being provided to permit a filling of the substantially enclosed pressure-generating chamber 30 disposed in the lower portion of the tank structure 106. The first con-

tact structure 55 in this instance comprises a pair of hollow contacts 111, 112, the first of which is rigidly secured to a metallic plate 113, and the second of which is movable and secured to a conducting contact rod 114 having a flange 115 integrally formed therewith.

The second contact structure, in this instance comprises a hollow stationary contact 116 having a conducting tubular extension 117, the upper end of which communicates with the interrupting chamber 56 by suitable conduit means in this instance assuming the form of a pipe 118. Valve means generally designated by the reference numeral 119 closes the conduit means 118 upon a predetermined pressure within the interrupting chamber 56 as determined by the piston 120 and compression spring 121. An overpressure valve 122 may be provided in an insulating cap 123 closing the upper end of the interrupting chamber 56 which is formed by an insulating cylinder 124.

The movable pressure-generating contact 125 is actuated in a reciprocal vertical direction by an insulating operating rod 126 latched upwardly in its closed circuit position by a latching device generally designated by the reference numeral 127 and comprising an armature 128 associated with a solenoid 129.

A compression spring 130 is disposed between 30 a cap 131 and a flange 132 integrally formed with the insulating operating rod 126, thereby biasing the movable pressure-generating contact 125 downwardly towards its open circuit position.

From the foregoing description it is apparent 35 that in the closed circuit position of the interrupter as shown in Fig. 7, the electrical circuit therethrough comprises terminal stud 133 extending through bushing 134, connector 135, bolt 136, connector 137, movable pressure-generating contact 125, stationary pressure-generating contact 116, tubular extension 117, conducting conduit 118, conducting cup-shaped member 138, flexible strap 139, conducting plate 113, stationary interrupting contact 111, movable interrupting contact 112, conducting contact rod 114, flexible strap 140 140 to terminal bolt 141 to which a terminal lug 142 may be rigidly secured.

To open the electrical circuit passing through the interrupter the latching device 127 is actuated 50 either manually or in response to overload conditions existing in the circuit controlled by the interrupter to permit the compression spring 130 to force the insulating operating rod 126 downwardly so that the movable pressure-generating contact 125 engages the stop 143 integrally formed with the insulating cup-shaped member 144. This establishes a pressure-generating arc, not shown, within the pressure-generating chamber 30 which reacts upon the oil disposed therein to create gaseous pressure. This gas under pressure acts upwardly through the guide spider 145, upwardly through the tubular extension 117, conduit 118 and into the interrupting chamber 56. When the interrupting chamber 56 has attained a predetermined superimposed static gaseous pressure, the piston 120 will be moved toward the left against the biasing action of the compression spring 121 to cause the valve means 119 to close the conduit means 118.

Meanwhile, the pressure-generating arc continues to raise the pressure within the pressure-generating chamber 30 and thereby causes the same to expand by upward movement of the piston 146 moving upwardly within the piston cylinder 147, the lower end of which is threaded se-

cured at 148 to the partition member 107. The upward movement of the piston 146 takes place in opposition to the compression spring 149 disposed in the upper portion of the piston cylinder 147. The piston 146 has rigidly secured thereto a piston rod 150 having a pin 151 passing therethrough at its lower end. Following a predetermined upward movement of the piston 146, the pin 151 engages the bifurcated portion 152 of a lever 153 pivotally mounted intermediate its ends at 154 to a bracket 155 which may be secured in any suitable manner, as by welding, to the lower metallic plate 156 of the tank structure 106.

The left-hand end of the lever 153 has a slot 157 formed therein through which extends a pin 158 secured to and movable with the contact rod 114.

Consequently, upon a predetermined upward movement of the piston 146 in response to a predetermined pressure rise within the pressure generating chamber 30 the contact rod 114 will be forcibly moved downwardly to thereby separate the first contact structure 55 thereby establishing an interrupting arc between the cooperable contacts 111, 112. Practically simultaneously with the separation of the first contact structure 55 the flange 115 secured to the contact rod 114 opens the valve 159 which closes an aperture 160 provided through the lower end of the casing 124 to thereby permit intercommunication between the pressure-generating chamber 30 and the interrupting chamber 56.

When this occurs fluid under pressure will pass from the pressure-generating chamber 30 through the aperture 160 through a plurality of tubes 161 composed of insulating material and radially inwardly between the separating contacts 111, 112. After contacting the interrupting arc this fluid will exhaust either upwardly through the hollow stationary interrupting contact 111 or downwardly through the hollow movable interrupting contact 112 out ports 162 into region 163 upwardly through insulating tubes 164 to the region 165.

The result is a rapid extinction of the interrupting arc drawn between the contacts 111, 112 in a region of superimposed pressure.

It will be noted that downward movement of the contact rod 114 causes a piston 166 to move downwardly within a dash-pot generally designated by the reference numeral 167 and comprising a piston cylinder 168 and a check valve 169, biased to its closed position by a compression spring 170. Once the piston 166 is disposed within the lower end of the dash-pot 167 it will rise upwardly slowly because of the small bleeder opening 171 provided in the piston cylinder 168. A compression spring 172 is provided in the dash-pot 167 to bias the piston 166 upwardly.

From the foregoing description it will be apparent that in this embodiment of my invention I separate the second contact structure first, thereby forming a pressure-generating arc, the pressure established adjacent to it being first utilized to create a superimposed pressure within the interrupting chamber 56. Subsequently, a higher pressure generated within the pressure-generating chamber 30 causes the opening of the first contact structure drawing an interrupting arc and effecting the extinction thereof by a flow of fluid passing from the pressure-generating chamber 30 into the interrupting chamber 56 under a higher pressure than that initially used in establishing the superimposed pressure within the interrupting chamber 56. The dash-pot 167

is employed to temporarily maintain the first contact structure open. Disconnect means disposed externally of the tank structure 106 may be employed to effect an isolating gap in the circuit, or the movable parts may be latched in their open circuit position.

When it is desired to close the circuit passing through the interrupter, suitable means, not shown, may be employed to effect upward movement of the insulating operating rod 126 to effect a closure between the contacts 116, 125 and permitting a latching of the latching device 127 to take place.

It will be observed that upon the attainment of excessive pressure within the pressure-generating chamber 30 that this pressure will act upon the projected area of the insulating operating rod 126 to force the latter upwardly against the downward biasing action of the compression spring 130, thereby shortening the length of the pressure-generating arc. Thus, in this embodiment of my invention I have again provided means for shortening the length of the pressure-generating arc upon the attainment of excessive pressure within the pressure-generating chamber 30.

The device shown in Fig. 7 illustrates an arrangement by means of which the pressure-generating arc builds up a superimposed pressure of some definite value, but smaller than the pressure in the pressure chamber 30 before the main contacts 111, 112 open. A pressure release valve 122 is also employed in conjunction with the interrupting chamber 56.

From the foregoing description it is apparent that I have provided an improved interrupter in which the pressure formed in the pressure generating chamber 30 will cause a reclosure of the pressure-generating contacts 116, 125 when the force on the projected area of the insulating operating rod 126 exceeds the downward force exerted by the compression spring 130. Thus, the pressure is controlled within the pressure generating chamber 30.

The above disclosure indicates how my invention may be applied to circuit interrupters of widely different types. Although my invention has been disclosed using oil as the interrupting medium, it is apparent that gas could be employed. I have shown how superimposed pressure may be created within the interrupting chamber by utilizing a portion of the pressure generated at the pressure-generating arc. Subsequently, a higher pressure may be employed to drive fluid from the pressure-generating arc toward the interrupting arc to effectively quench the latter.

Although I have shown and described several specific structures, it is to be clearly understood that the same were merely for the purpose of illustration and that changes and modifications may readily be made therein by those skilled in the art without departing from the spirit and scope of the appended claims.

65 I claim as my invention:

1. In a circuit interrupter, means defining a substantially enclosed interrupting chamber within which an interrupting arc is established, means defining a substantially enclosed pressure-generating chamber within which a pressure-generating arc is established, conduit means interconnecting the two chambers, valve means disposed in the conduit means closing the same upon a predetermined rise of pressure within the 70 interrupting chamber, and means establishing 75

intercommunication between the two chambers at a predetermined pressure within the pressure-generating chamber which is higher in magnitude than the pressure necessary to close the valve means in the conduit means.

2. In a circuit interrupter, means defining a substantially enclosed interrupting chamber within which an interrupting arc is established, means defining a substantially enclosed pressure-generating chamber within which a pressure-generating arc is established, conduit means interconnecting the two chambers, valve means disposed in the conduit means closing the same upon a predetermined rise of pressure within the interrupting chamber, means permitting an intercommunication between the two chambers at a predetermined pressure within the pressure-generating chamber which is higher in magnitude than the pressure necessary to close the valve means in the conduit means, and means for shortening the length of the pressure-generating arc upon the attainment of excessive pressure within the pressure-generating chamber.

3. In a circuit interrupter, a first contact structure to draw an interrupting arc, a second contact structure to draw a pressure-generating arc, a piston member, a substantially enclosed pressure-generating chamber within which the pressure-generating arc is established and having one wall thereof formed by the piston member, the piston member being responsive to the pressure within the pressure-generating chamber, and a lost-motion mechanical connection interconnecting the piston member and the first contact structure to cause the actuation of the same.

4. In a circuit interrupter, a partition member, means defining adjacently disposed interrupting and pressure-generating chambers separated by a partition member, a piston member having a piston rod, one wall of the pressure-generating chamber being formed by the piston member, and the piston rod being slidable through the partition member.

5. In a circuit interrupter, a partition member, means defining adjacently disposed interrupting and pressure-generating chambers separated by the partition member, a piston member having a piston rod, one wall of the pressure-generating chamber being formed by the piston member, the piston rod being slidable through the partition member, first contact structure disposed in the interrupting chamber to draw an interrupting arc, and a lost-motion mechanical connection interconnecting the piston rod and the first contact structure to cause the actuation of the same.

6. In a circuit interrupter, a partition member, means defining adjacently disposed interrupting and pressure-generating chambers separated by the partition member, a piston member having a piston rod, one wall of the pressure-generating chamber being formed by the piston member, the piston rod being slidable through the partition member, first contact structure disposed in the interrupting chamber to draw an interrupting arc, a lost-motion mechanical connection interconnecting the piston rod and the first contact structure to cause the actuation of the same, a second contact structure disposed within the pressure-generating chamber cooperable to establish a pressure-generating arc and comprising a contact secured to and movable with the piston member.

7. In a circuit interrupter, a partition member, means defining adjacently disposed interrupting

and pressure-generating chambers separated by the partition member, a piston member having a piston rod, one wall of the pressure-generating chamber being formed by the piston member, the piston rod being slidable through the partition member, first contact structure disposed in the interrupting chamber to draw an interrupting arc, a lost-motion mechanical connection interconnecting the piston rod and the first contact structure to cause the actuation of the same, a second contact structure disposed within the pressure-generating chamber cooperable to establish a pressure-generating arc and comprising a contact secured to and movable with the piston member, a ring-shaped conducting member disposed within the pressure-generating chamber and surrounding the piston rod, the second contact structure also comprising a contact secured to the ring-shaped conducting member.

8. In a circuit interrupter, a partition member, means defining adjacently disposed interrupting and pressure-generating chambers separated by the partition member, a piston member having a piston rod, one wall of the pressure-generating chamber being formed by the piston member, the piston rod being slidable through the partition member, first contact structure disposed in the interrupting chamber to draw an interrupting arc, a lost-motion mechanical connection interconnecting the piston rod and the first contact structure to cause the actuation of the same, a second contact structure disposed within the pressure-generating chamber cooperable to establish a pressure-generating arc and comprising a contact secured to and movable with the piston member, a ring-shaped conducting member disposed within the pressure-generating chamber and surrounding the piston rod, the second contact structure also comprising a contact secured to the ring-shaped conducting member, means biasing the ring-shaped conducting member away from the piston member, and means comprising one or more operating rods for maintaining the second contact structure in abutting engagement in the closed circuit position.

9. In a circuit interrupter, a partition member, means defining adjacently disposed interrupting and pressure-generating chambers separated by the partition member, a piston member having a piston rod, one wall of the pressure-generating chamber being formed by the piston member, the piston rod being slidable through the partition member, first contact structure disposed in the interrupting chamber to draw an interrupting arc, a lost-motion mechanical connection interconnecting the piston rod and the first contact structure to cause the actuation of the same, a second contact structure disposed within the pressure-generating chamber cooperable to establish a pressure-generating arc and comprising a contact secured to and movable with the piston member, a ring-shaped conducting member disposed within the pressure-generating chamber and surrounding the piston rod, the second contact structure also comprising a contact secured to the ring-shaped conducting member, the ring-shaped member having a portion extending through the piston member.

10. In a circuit interrupter, a partition member, means defining adjacently disposed interrupting and pressure-generating chambers separated by the partition member, a piston member having a piston rod, one wall of the pressure-generating chamber being formed by the piston member, the piston rod being slidable through

the partition member, first contact structure disposed in the interrupting chamber to draw an interrupting arc, a lost-motion mechanical connection interconnecting the piston rod and the first contact structure to cause the actuation of the same, a second contact structure disposed within the pressure-generating chamber cooperable to establish a pressure-generating arc and comprising a contact secured to and movable with the piston member, a ring-shaped conducting member disposed within the pressure-generating chamber and surrounding the piston rod, the second contact structure also comprising a contact secured to the ring-shaped conducting member, means biasing the ring-shaped conducting member away from the piston member, and means comprising one or more operating rods for maintaining the second contact structure in abutting engagement in the closed circuit position, the ring-shaped member having a portion extending through the piston member.

11. In a circuit interrupter, a partition member, means defining adjacently disposed interrupting and pressure-generating chambers separated by the partition member, a piston member having a piston rod, one wall of the pressure-generating chamber being formed by the piston member, the piston rod being slidable through the partition member, and the piston rod having one or more flutes formed therein to permit intercommunication between the two chambers after a predetermined opening movement of the piston member.

12. In a circuit interrupter, an operating rod, an electromagnetic device for raising the operating rod upon predetermined overload conditions, means defining adjacently disposed interrupting and pressure-generating chambers, a partition member separating the two chambers, a piston member having a fluted piston rod forming the lower wall of the pressure-generating chamber, the piston rod passing slidably through the partition member, first contact structure disposed within the interrupting chamber and cooperable to establish an interrupting arc, a lost-motion mechanical connection, the first contact structure being interconnected by the lost-motion mechanical connection to the piston member, a ring-shaped member disposed within the pressure-generating chamber and surrounding the piston rod, second contact structure disposed within the pressure-generating chamber cooperable to establish a pressure-generating arc therein and comprising a contact secured to and movable with the piston member and a contact secured to the ring-shaped member, a conducting portion of the ring-shaped member extending through the piston member, means biasing the ring-shaped member upward away from the piston member, and means biasing the operating rod downward to hold the contact secured to the ring-shaped member in abutting engagement with the contact secured to the piston member.

13. In a circuit interrupter, an arc extinguishing unit, an operating rod extending through the lower wall of the unit, a pressure-generating chamber disposed adjacent the upper end of the unit, an interrupting chamber disposed adjacent the lower end of the unit, a conducting bridging member for actuating the operating rod, a piston member forming the upper wall of the pressure-generating chamber and having a fluted piston rod secured thereto, a partition member separating the two chambers, the piston rod passing slidably through the partition member, first con-

tact structure disposed in the interrupting chamber, a lost-motion mechanical connection, the first contact structure being connected by the lost-motion mechanical connection to the piston member, a second contact structure disposed within the pressure-generating chamber and comprising a contact secured to and movable with the piston member, a ring-shaped member carrying a contact, the operating rod forcing the contact secured to the ring-shaped member against the contact secured to the piston in the closed circuit position of the interrupter.

14. A circuit interrupter including means comprising a piston for defining a substantially enclosed pressure-generating chamber, means for establishing a pressure-generating arc within the pressure-generating chamber, means defining an adjacently disposed interrupting chamber, means for establishing an interrupting arc within the interrupting chamber, wall means separating the two chambers, opening means for the wall means including the piston which forms one wall of the pressure-generating chamber and is movable in response to increase of pressure therein to thereby appreciably increase the volume thereof, the opening means establishing intercommunication between the two chambers upon a predetermined rise of pressure within the pressure-generating chamber, and means operatively connecting the piston with the means for establishing the interrupting arc.

15. In a circuit interrupter of the liquid-break type, a first contact structure to draw an interrupting arc within liquid, a second contact structure to draw a pressure-generating arc within liquid, a piston member, a substantially enclosed pressure-generating chamber containing liquid within which the pressure-generating arc is established and having one wall thereof formed by the piston member, the piston member being responsive to the pressure within the pressure-generating chamber, and a lost-motion mechanical connection interconnecting the piston member and the first contact structure to cause the actuation of the same.

16. In a circuit interrupter, a first contact structure operable to draw an interrupting arc within an interrupting chamber, a second contact structure to draw a pressure-generating arc, a piston member, a substantially enclosed pressure-generating chamber within which the pressure-generating arc is established and having one wall thereof formed by the piston member, the piston member being responsive to the pressure within the pressure-generating chamber, means causing intercommunication between the pressure-generating chamber and the interrupting chamber, and a lost-motion mechanical connection interconnecting the piston member and the first contact structure to cause the actuation of the same.

17. In a circuit interrupter, means defining an interrupting chamber, a first contact structure to draw an interrupting arc within the interrupting chamber, a second contact structure to draw a pressure-generating arc, a piston member, a substantially enclosed pressure-generating chamber within which the pressure-generating arc is established and having one wall thereof formed by the piston member, the piston member being responsive to the pressure within the pressure-generating chamber, means establishing intercommunication between the pressure-generating chamber and the interrupting chamber following the attainment of a predetermined pressure

within the pressure-generating chamber, and a lost-motion mechanical connection interconnecting the piston member and the first contact structure to cause the actuation of the same.

18. In a circuit interrupter, means defining an interrupting chamber, a first contact structure to draw an interrupting arc within the interrupting chamber, a second contact structure to draw a pressure-generating arc, a piston member, a substantially enclosed pressure-generating chamber within which the pressure-generating arc is established and having one wall thereof formed by the piston member, the piston member being responsive to the pressure within the pressure-generating chamber, conduit means interconnecting the two chambers, valve means disposed in the conduit means closing the same upon a predetermined rise of pressure within the interrupting chamber, means establishing intercommunication between the two chambers at a predetermined pressure within the pressure-generating chamber which is higher in magnitude than the pressure necessary to close the valve means in the conduit means, and a lost-motion mechanical connection interconnecting the piston member and the first contact structure to cause the actuation of the same.

19. A circuit interrupter of the liquid-break type including means comprising a piston for defining a substantially enclosed pressure-generating chamber containing liquid, means for establishing a pressure-generating arc within the pressure-generating chamber, means defining an adjacently disposed interrupting chamber containing liquid, means for establishing an interrupting arc within the liquid disposed within the interrupting chamber, wall means separating the two chambers, opening means for the wall means including the piston which forms one wall of the pressure-generating chamber and is movable in response to increase of pressure therein to thereby appreciably increase the volume thereof, the opening means establishing intercommunication between the two chambers upon a predetermined rise of pressure within the pressure-generating chamber, and means operatively connecting the piston with the means for establishing the interrupting arc.

20. A circuit interrupter including means comprising a piston for defining a substantially enclosed pressure-generating chamber, means for establishing a pressure-generating arc within the pressure-generating chamber, means defining an adjacently disposed interrupting chamber, means

for establishing an interrupting arc within the interrupting chamber, wall means separating the two chambers, opening means for the wall means including the piston which forms one wall of the pressure-generating chamber and is movable in response to increase of pressure therein to thereby appreciably increase the volume thereof, the opening means establishing intercommunication between the two chambers upon a predetermined rise of pressure within the pressure-generating chamber, and means operatively connecting the piston by a lost-motion mechanical connection with the means for establishing the interrupting arc.

21. A circuit interrupter including means comprising a piston for defining a substantially enclosed pressure-generating chamber, means for establishing a pressure-generating arc within the pressure-generating chamber, means defining an adjacently disposed interrupting chamber, means for establishing an interrupting arc within the interrupting chamber, conduit means interconnecting the two chambers, valve means disposed in the conduit means closing the same upon a predetermined rise of pressure within the interrupting chamber, wall means separating the two chambers, opening means for the wall means including the piston which forms one wall of the pressure-generating chamber and is movable in response to increase of pressure therein to thereby appreciably increase the volume thereof, the opening means establishing intercommunication between the two chambers upon a predetermined rise of pressure within the pressure-generating chamber, and means operatively connecting the piston with the means for establishing the interrupting arc.
